UNITED STATES PATENT OFFICE.

HARRY M. NEER, OF COLUMBUS, OHIO.

VALVE-CONTROLLING MECHANISM FOR INTERNAL-COMBUSTION ENGINES.

No. 901,365.

Specification of Letters Patent.

Patented Oct. 20, 1908.

Application filed February 13, 1908. Serial No. 415,631.

To all whom it may concern:

Be it known that I, HARRY M. NEER, citizen of the United States, residing at Columbus, in the county of Franklin and State of Ohio, have invented certain new and useful Improvements in Valve-Controlling Mechanism for Internal-Combustion Engines, of which the following is a specification.

My invention relates to the improvement of valve controlling mechanism for internal combustion engines and the objects of my invention are to provide an engine of this class with improved means for positively opening and closing the intake and exhaust valves at proper intervals, thereby obviating the loss of compression which sometimes occurs in high speed engines through the failure of one of said valves to close at the proper moment; to so construct my improved valve controlling apparatus as to obviate the necessity of employing springs for the opening or closing of said valves and to produce other improvements the details of which will be more fully pointed out herein-after. These objects I accomplish in the manner illustrated in the accompanying drawing, in which:

Figure 1 is a vertical section through the crank case and an exhaust and intake valve 30 of a gasolene engine, Fig. 2 is a side elevation of a bevel gear wheel and its attached guide plate or shield which I employ in the manner hereinafter described, Fig. 3 is a plan view of said gear wheel, and, Fig. 4 is a transverse section of the guide or shield plate which I employ in connection with said beveled gear wheel.

Similar numerals refer to similar parts throughout the several views.

1 represents the crank case of a gas or gasolene engine, 2 the crank shaft mounted therein, 3 the fly wheel which is mounted on said shaft, 4 and 5 the cranks from which are operated the connecting rods in the usual manner, a portion of one of said rods being indicated at 6.

7 represents a fan which is mounted on a reduced extension 2^a of the main shaft and which is inclosed in a fan casing 8, the latter having an air conducting pipe 9 leading therefrom, through which air from the fan is forced to the engine cylinders. These cylinders of which there are two shown in the drawing, are indicated at 10 and 11, said cylinders being provided in the usual man-

ner with pistons operated by the connecting rods, said pistons not being herein shown.

Upon the shaft 2, is carried a gear wheel 12 which meshes with a gear wheel 13 carried on one end of a horizontal shaft 14 journalled in the crank case. The shaft 14 carries for each pair of exhaust and inlet valves employed a bevel pinion 15, each of these pinions gearing with a horizontal bevelled gear wheel 16 which is rotatably mounted upon a short vertical pin or shaft 17 which rises from a fixed frame arm 18 in which the shaft 14 is also journalled. In the construction of the bevelled gear wheel 16, I form the otherwise flat upper side of the same with a cam projection 19 which is in the nature of a one-quarter segment of a ring or band rising from the upper surface of the gear wheel adjacent to its periphery. The ends of this cam segment 19 are inclined, as shown, to meet the upper face of the gear wheel. It will be noted that the pinion 15 is of half the size of said gear wheel 16.

Mounted on an upward extension 17^a of the shaft 17 is the central portion of a disk or plate 20, the latter having a depressed marginal portion which is shown at 20^a and which depressed portion occupies three-fourths of the circumference of the disk top. Through the medium of pins 21 which project upwardly from each of the gear wheels 16, the disk 20 is held against independent rotary movement and in such position that the undepressed fourth of the marginal portion of the disk is located immediately above the cam projection 19 on said gear wheel, thus providing an equal distance between the marginal portion of the disk and the top of the gear wheel and between said disk and the upper surface of the cam projection 19. The upper ends of the pins 21 pass loosely through openings in the disk and the upper side of the disk has a cushion bearing against a short coiled spring 17^b which bears between said disk and the enlarged head of the shaft extension 17^a.

22 and 23 represent respectively an exhaust and intake valve casing, these casings being, as shown, in connection with the head of one of the engine cylinders and having downwardly extending valve rod guide projections 24.

25 represents an exhaust valve and 26 an intake valve, these valves being located in

their respective casings and adapted to seat in the lower portion thereof. From the exhaust valve 25 leads downward the usual valve rod 27 which passing into the crank 5 casing has pivoted in its lower end a small roller 28. A similar roller 29 is pivotally connected with the lower end of the valve rod 30 of the intake valve 26.

As indicated in Fig. 1 of the drawing, 10 the rollers 28 and 29 are adapted to bear and roll upon the upper surfaces of the gear wheel and the cam projection 19 thereof.

It is obvious that when one of the valve rod rollers is upon the cam projection 19, 15 the valve of the rod with which said raised roller is connected, will be held in the open position and that that valve the rod of which has its roller bearing upon the surface of the beveled gear wheel, will be closed. In 20 order to insure this contact of the rollers with the surface of the gear wheel and thereby insure the closing of the valve, I provide the lower end of each of the valve rods 27 and 30 with a laterally projecting stud or 25 pin 31 which as shown in Fig. 1 of the drawing, engages the underside of the marginal portion of the disk 20.

In operation it is obvious that the rotation of the crank shaft will impart through 30 the gear wheels 12 and 13, rotary motion to the shaft 14 which through its pinions 15 will impart rotary motion to the gear wheels 16. In the movement of each of these gear 35 wheels, it will be understood that at regular intervals the rollers 28 and 29 will successively ride upon the cam projection 19 of the gear wheel and upon the upper surface of said wheel, thereby producing at certain predetermined times a positive opening and 40 closing operation of the exhaust and inlet valves without the aid of springs or other mechanical devices.

Heretofore considerable difficulty has been experienced in internal combustion engines 45 of this character in maintaining power owing

to the failure of the valves to close or open at the proper time, but it will be noted that the means herein described are such as to insure a positive closing and opening action of the valves, these means being so constructed and arranged as to not only open the intake valve to admit the charge of gas and air, but to close said valve and hold it closed while the charge is being compressed. Likewise the means employed are 55 so arranged as to hold the exhaust valve closed during compression and open said exhaust valve on the exhaust stroke of the piston and close the same before the intake valve opens. 60

It will be observed that the mechanism by which these objects are accomplished is simple of construction and of such nature as to insure positive operation.

What I claim, is:

In an internal combustion engine, the combination with a crank case, a crank shaft therein, connecting rod, operating cranks on said crank shaft, piston containing cylinders, exhaust and inlet valve casings, valves in 70 said casings and valve rods extending therefrom into said crank case, and a roller pivoted in each of said valve rods, of a shaft within the crank case rotated by the crank shaft, a pinion carried on said shaft, a gear 75 wheel meshing with said pinion, a cam segment on the upper side of said gear wheel, and a plate supported above said gear wheel, and having a depressed portion, said valve rod rollers adapted to bear on said gear 80 wheel and its cam projection and the lower ends of said rods adapted to engage the underside of said plate.

In testimony whereof I affix my signature in presence of two witnesses.

HARRY M. NEER.
